Primary Examiner — Kevin Rudzinski*Assistant Examiner* — Paul Bohannon(74) Attorney, Agent, or Firm — Warner Norcross & Judd LLP(57) CLAIM

The ornamental design for fragrance container, as shown and described.

DESCRIPTION

FIG. 1 is a perspective view of the fragrance container embodying the new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

FIGS. 1-7 show features of a fragrance container in phantom lines. These features are shown for environmental purposes and do not form any part of the claimed design. Further, the phantom lines immediately adjacent the solid-line portions of the design form the boundary of the design, with the phantom lines forming no part of the claimed design.
